Filed Mar. 29, 1960, Ser. No. 59,928

Term of patent 14 years

(Cl. D3—26)

FIG. 1.

FIG. 2.

FIG. 3.

FIG. 4.

FIG. 1 is a rear perspective view of a child's dress showing my new design, the front of the child's dress being conventional in appearance;

FIG. 2 is a plan view of the wing-like decoration shown in FIG. 1;

FIG. 3 is a plan view of a modified form of wing-like decoration having a lace edging; and

FIG. 4 is a plan view of a further modified form of wing-like decoration having fluted edging.

The dominant feature of my design resides in the wing-like decoration shown in full lines.

I claim:

The ornamental design for a child's dress, substantially as shown and described.
